TABLE STRUCTURE

Application filed May 21, 1928. Serial No. 279,330.

This application is a continuation in part of my application filed January 3, 1928, Serial No. 244,207, for improvement in wall furniture.

5 The object of this invention is to provide an improved foldable table and bench structure which is capable of being compacted or collapsed within a relatively small space when not desired for use.

10 A further object of the invention is to provide an improved table and bench structure which is especially designed for kitchenettes and the like and which is capable of being folded and collapsed within a casing which

15 may be a part of the wall of a room so that when the structure is collapsed it is completely concealed within the casing and occupies none of the room space.

Still another object is to provide a structure of the class described, in which the table top forms a closure for a casing and serves to cover and conceal the other elements of the structure.

Another and further object of the invention 25 is to provide a structure of the class described, which is economical to build, which is easily installed, and which is especially convenient and effective for the purpose for which it is designed.

30 With these and other objects in view my invention consists in the construction, arrangement and combination of the various parts of my device, whereby the objects contemplated are attained, as hereinafter more fully set forth, pointed out in the claims, and illustrated in the accompanying drawings, in which:

Fig. 1 is a perspective view showing the 40 manner in which the elements of the device may be collapsed within a casing when not desired for use.

Fig. 2 is a perspective view showing the structure in extended position, as required 45 for use.

Fig. 3 is a cross-section on the line 3—3 of Fig. 2, the dotted lines indicating positions assumed by the parts when in folded condition.

50 Fig. 4 is a front elevation partly in section,

illustrating the structure in extended position.

Fig. 5 is a plan view showing the device in partly extended position as when desired for use as a table only.

55 Fig. 6 is a perspective view illustrating a modified form in which the casing is not built into a wall, but is movable and is utilized for receiving two units of the table and bench structure, whereby a relatively long table is 60 provided.

Fig. 7 is a detail section on the line 7—7 of Fig. 6 and illustrating particularly, one of the benches employed in the modified structure.

65 Fig. 8 is a perspective view of a portion of the built-in structure, illustrating particularly, the method of folding the elements comprising one of the benches.

Fig. 9 is a detail section on the line 9—9 of Fig. 2, illustrating the stop and latch for holding one of the wings relative to the table 70 top.

Fig. 10 is a detail vertical section illustrating the method of hinging the table top with 75 in the casing.

Fig. 11 is a horizontal section through the casing, a portion being broken away to economize space, showing particularly, the method of hinging the two wings within the casing.

80 Fig. 12 is a detail of a special knob.

The preferred embodiment of my invention involves a table top and a pair of benches, usable therewith and carried by the wings 85 which support the table top, the benches being foldable into the wings and the wings being foldable into parallel planes within a casing, after which the table cover or top is foldable downwardly to provide a door for 90 the casing so that all of the elements may be completely inclosed and yet be readily accessible for use. This structure is designed particularly for use in kitchenettes and the like, where the greatest economy must be ob-

95 served as to room space, or in other situations where a table and bench are needed only a part of the time. When so employed, the casing may be built into a wall of the room in such manner that when the structural elements 100

are completely collapsed within the casing there are no parts projecting within the room.

My invention also involves the utilization of the same principles of construction in a double unit which comprises a pair of table top members, each having a pair of wings for supporting it in horizontal position and a bench carried by and foldable relative to each of the wings. The two table top members are hinged on opposite sides of a portable casing within which all of the elements are capable of being folded and so arranged that the two table top members provide doors at opposite sides of the casing for covering and concealing the other elements. This embodiment of my invention is illustrated in Figs. 6 and 7 of the drawings.

In the form of my invention which includes the built-in feature, a casing is employed which comprises a rear wall 12, a top wall 14, a bottom wall 16, and spaced end walls 18. This casing may be of any desired height and length, but is relatively shallow and may be built into the wall 20 of a building so as to open to one side of said wall and into a room of the building.

At its open side, the casing preferably is provided with trimming or facing, such as 22 to conform with the woodwork of the room.

If preferred, the casing may be in the nature of a cabinet to contain the table and bench structure and the cabinet may be of any desired size and shape and finished in any desired manner.

A pair of wings are provided and are foldable within the casing. Each of the wings is of substantially U-shape and comprises a vertical end member 24 having a horizontally projecting upper arm 26 and a horizontally projecting lower arm 28. The vertical member 24 of each U-shaped wing is hinged to one of the end walls 18 of the casing or cabinet by means of spring hinges 30.

One of the wings is hinged within the casing at a point nearer to the rear wall 12 than is the other wing, in order that said wings may be folded within the casing in positions substantially parallel with each other and with said rear wall as illustrated particularly in Fig. 11 and the spring 30' of that wing which is nearer to the rear wall is so arranged as to tend to carry its wing toward folded position, while the spring 30'' of the other wing is so arranged as to tend to carry its wing to extended position. The particular purpose of this arrangement is to cause the innermost or rearmost wing to move first, toward folded position, in order that there may be no trouble about getting the wings in their proper relative positions when the device is collapsed.

A brace 31, which may be a metallic strap, preferably is mounted on the inner face of each of the wings, but extends partially

across the vertical member 24 and particularly along the upper horizontal arm 26.

I have also provided a table top member designated by the numeral 32 and said member is hinged to the upper forward part of the casing by a hinge means, shown particularly in Fig. 10. This hinging means includes a plate 34 countersunk in the edge of the table member 32 and carrying a pintle pin 36 which projects laterally and is received within a plate 38 countersunk in the adjacent face of one of the end walls 18 of the casing. This permits the table top member 32 to be extended to horizontal position outwardly from the upper part of the casing or to be lowered to a vertical position in which it forms a door for the open side of the casing.

The table top 32 is supported in horizontal or extended position by moving the wings outwardly of the casing, as shown in Figs. 2 and 3, in which position the upper arms 26 of the wings engage beneath and near the side margins of the member 32.

I consider it advisable to provide means for limiting the outward swinging movement of the wings and also for latching them to the table top 32 and for this purpose have provided angle bars 40 at opposite sides of the table member 32. Each of the angle bars has one of its arms fixed to the lower face of the table member 32 by means of screws 42 and extending laterally thereof and having its other member extending downwardly near the edge of the table to limit outward movement of one of the wings by engagement with the upper arm 26 thereof. The latching means may comprise a snap fastener including a socket 44 carried by the downwardly projecting member of each angle bar 40 and engageable by a spring stud 46 carried by the upper arm 26 of each wing, as shown particularly in Fig. 9.

I have also shown the table top member 32 as provided with a leaf 48 hinged to its outer margin and adapted to form an extension thereof. The leaf 48 is hinged to the table top 32 by means of hinges 50 located on the lower faces of said members so that the leaf 48 may be dropped or be folded behind the member 32 at times.

The leaf 48 is held in horizontal position by the outer ends of the upper arms 26 of the wings, as shown in Figs. 2 and 3.

I have also provided means whereby a bench may be carried by each of the wings and be arranged for convenient use at either end of the table when the device is in extended position.

Each of the benches comprises a seat member 52 and a pair of leg members 54 and 56.

The leg members 54 and 56 of each bench are hinged to the lower side of the seat member 52 by hinges 58 and are foldable into the same plane beneath said seat member at times.

5 The seat member 52 of each bench is hinged to the lower arm 28 of one of the wings by means of hinges 60 and is foldable into a position between the lower and upper arms of the wing at times.

10 The folded position of one of the benches relative to the wing which carries it is shown particularly in Fig. 8 and in this view I have also shown a latch 62 for holding the seat member 52 in this folded position.

15 It will be observed that when the bench is folded relative to the wing which carries it, the seat member 52 is in the same plane as the upper wing 26 and lower wing 28 and that the legs 54 and 56 are in a parallel plane and are folded flat against that face of the seat member which is the lower face when the bench is extended for use.

20 Assuming the parts to be in fully extended position, as shown in Figs. 2 and 3, they may be collapsed by raising the seat members 32 of the benches until the latches 62 engage and hold the benches in the folded position. The legs 54 and 56 are then folded against 25 the rear or outer faces of the seat members. The wings are then released by manual pressure on their outer faces to disengage the spring studs 46 from the sockets 44, after which the wings are folded within the casing. That wing which is hinged nearer to 30 the rear wall 12 of the casing is, of course, folded in first, which action may be caused automatically by the spring 30' of its hinge. It will be observed that space is provided between the two wings for the legs of the bench carried by the rearmost wing and that there is space between the outermost wing and the mouth of the casing for the legs of the bench which are carried by that wing.

40 As soon as the wings are out of the way, the table member 32 may be lowered to vertical position across the front of the casing, the leaf 48 first being folded back behind said member 32. To hold the table members in closed position, I have shown a stud or lug 64 mounted on the lower or rear side of the member 32 near its free margin and adapted to enter a spring catch member 66 carried by the bottom wall 16 of the casing.

45 The line of meeting of the leaf 48 with the table member 32 may be any desired formation, but I prefer to form it so as to produce one or more curves, as shown particularly in Fig. 2, the result of which formation is to produce one or more notches 68 in the lower or outer margin of the member 32, as is most clearly shown in Fig. 1. These notches serve as hand-holds to facilitate the opening and raising of the member 32 and permit the application of manual force to disengage the member 64 from the catch 66.

50 The numeral 70 designates stops which are fixed to and project downwardly from the inner face of the upper arm 26 of each wing to limit the movement of the bench seats 52

toward collapsed position and to prevent undue strain on the hinges and latches of said seats.

55 A cleat 71 is fixed to the outer face of the lower arm 28 of each wing and spans the space between the hinged legs 54 and 56 of the bench. One function of the cleat 71 is to engage the inner faces of the legs 54 and 56 when they are extended and prevent their movement to folded position until such time as the seat member 52 has been folded upwardly.

60 At times it may be desirable to use only the table top member 32 of the structure and in such event, the parts may assume the positions shown in Fig. 5, wherein one of the wings with the bench it carries remains folded within the casing, while the other of said wings may be used as a support for the table member 32 extending in an oblique direction beneath it, as shown by dotted lines. In this position, the extension leaf 48 hangs in a vertical position from the table member 32. If it is desired to use the extension member 48 as well as the top 32, both of the wings may be moved outwardly to their limit of motion to support the members 32 and 48 and, of course, either one or both of the benches may then be unfolded and extended whenever desired for use.

65 In Figs. 6 and 7, I have illustrated an embodiment of the invention in which the casing is not intended to be built into a wall, but is separately formed and is capable of being moved from place to place. The casing of this form of the invention is designed to carry and to form a closure for two units of the table and bench structure, such as have been hereinbefore described.

70 The casing, according to this form of the invention, is open at both sides and it comprises a top wall 140 and end walls 180. The casing may be provided with suitable internal braces, such as 72, to strengthen and support its members.

75 In this form of the invention, the elements previously described are duplicated at opposite sides of the casing and are similar in form to those hereinbefore described, except as specifically related herein.

80 The opposite sides of the casing, which naturally is somewhat wider than the built-in casing heretofore described, are closable by the two table top members 32 and in this instance, I have shown these members 32 without the extension leaves 48.

85 In Figs. 6 and 7, I have indicated that there is a bench at each end of each of the table members 32 and the seats 520 of said benches are hinged to the lower arms 280 of the respective foldable wings. In this instance, I have shown each bench as provided with a single leg or support designated by the numeral 540 and hinged to the outer margin of the seat member 520. In this construc-

tion it is desirable to provide the bench support 540 with toggle braces 74 to assist in strengthening the bench structure and to keep the supports 540 in normal vertical position for use.

As shown in Fig. 6, the parts are so arranged that the table members 32 when extended, occupy the same horizontal plane as the top wall 140 of the casing, whereby these three members form a continuous table top.

In this construction, I have also shown the lower arm 280 of each wing extended downwardly at its outer end as a leg 282 and having a caster or roller 284 at the lower end.

In Fig. 12 I have shown a disappearing knob for the table member 32, which may be employed if desired. This knob includes a stem 76 slidably mounted through the table member 32 and having a head 78 on its outer end and a stop 80 on its inner end. The head 78 is flat and when the table member 32 is raised, said head drops into a countersink hole 82 in the top of said table member so that the upper surface is smooth and plain. When the extension leaf 48 is folded behind the table member 32 it engages the stop 80 and moves the knob device outwardly to the position shown in Fig. 12, so that the head 78 may be clasped manually for the purpose of moving the table member to open position.

It is obvious that I have provided a table structure which is very convenient in use, as well as economical to manufacture, particularly because of the peculiar relation and cooperation of the various elements of the structure. It will be noted that the structure is low and compact and that it may be placed beneath a window or other similar location where it will be out of the way and occupy very little space. Also, that the casing may be arranged for attaching it to a wall instead of building it into the wall or having it portable.

Some changes may be made in the construction and arrangement of the parts of the device without departing from the real spirit and purpose of my invention, and it is my intention to cover by the claims, any modified forms of structure or use of mechanical equivalents, which may be reasonably included within their scope.

I claim as my invention:

1. A structure of the character described, comprising a casing open at one side, a wing hinged to one end wall of said casing and adapted to be folded therein, a table member hinged at the top of said casing and adapted to form a closure for the open side thereof, said wing being movable out of said casing and beneath said table member to support the latter in horizontal position, and a bench hinged to said wing and adapted to be extended to operative position adjacent one end of the table member.

2. A structure of the character described,

comprising a casing open at one side, a wing hinged to one end wall of said casing and adapted to be folded therein, a table member hinged at the top of said casing and adapted to form a closure for the open side thereof, said wing being movable out of said casing and beneath said table member to support the latter in horizontal position, and a bench hinged to said wing and adapted to be extended to operative position adjacent one end of the table member, said bench being provided with a hinged leg support adapted to be folded against the seat portion thereof.

3. A structure of the character described, comprising a casing open at one side, a wing hinged to each end wall of said casing and adapted to be folded therein, one wing in front of the other, a table member hinged at the top of said casing and adapted to form a closure for the open side thereof, said wings being movable out of said casing and beneath said table member to support the latter in horizontal position, a seat member hinged on and adapted to be folded relative to each of said wings, and means for supporting said seat members in operative position at the respective ends of said table member.

4. A structure of the character described, comprising a casing open at one side, a U-shaped wing hinged to one end wall of said casing and adapted to be folded therein, a table member hinged at the top of said casing and adapted to form a closure for the open side thereof, said wing being movable out of said casing and beneath said table member, whereby the upper arm of said wing constitutes a support for said table member, a seat hinged to the lower arm of said wing, and foldable means for supporting said seat in operative position.

5. A structure of the character described, comprising a casing open at one side, a U-shaped wing hinged to one end wall of said casing and adapted to be folded therein, a table member hinged at the top of said casing and adapted to form a closure for the open side thereof, said wing being movable out of said casing and beneath said table member, whereby the upper arm of said wing constitutes a support for said table member, a seat hinged to the lower arm of said wing, said seat being shaped to fit within and to substantially fill and being foldable into the space between the upper and lower arms of said U-shaped wing, and a supporting member hinged to said seat and adapted to hold it in operative position at times.

6. A structure of the character described, comprising a support, a wing having spaced horizontal arms, said wing being hinged to said support on a vertical axis, a table member hinged to said support on a horizontal axis, said wing being arranged to be extended beneath said table member with its upper arm

in supporting relation thereto, and a seat carried by the lower arm of said wing.

7. A structure of the character described, comprising a casing open at both sides, a table member hinged at the top on each side of said casing and adapted to close one side thereof and also adapted to be extended to horizontal position, supporting means hinged in said casing and adapted to be extended from each open side thereof to support the extended table members in extended position, and seat members carried by said supporting means and adapted to be folded therewith within said casing.

15 8. A structure of the character described, comprising a casing open at both sides, a table member hinged at the top on each side of said casing and adapted to close one side thereof and also adapted to be extended to horizontal 20 position, supporting means hinged in said casing and adapted to be extended from each open side thereof to support the extended table members in extended position, and seat members hinged to each of said supporting 25 means and adapted to be folded into vertical positions, whereby the supporting means and seat members may be folded within the casing and concealed by dropping said table members over the open sides thereof, together 30 with leg members hinged to said seat members.
